UNITED STATES PATENT OFFICE.

ARTHUR C. BADGER, OF NEWTON, MASSACHUSETTS.

FIRE EXTINGUISHER.

Application filed October 12, 1927. Serial No. 225,804.

This invention relates to fire extinguishers of the type of that shown in my prior application Serial No. 143,410, filed October 22, 1926, that is, the type using an originally 5 confined highly compressed gas, which is released at the instant of use, as the propelling force for discharging the extinguishing liquid, and in which the body of extinguishing liquid is arranged to submerge and 10 envelop the compressed gas holder during discharge, so as to deliver heat thereto and prevent liquefaction or solidification of the gas, due to loss of heat by expansion, when discharged under low temperature conditions. 15

The object of the invention is to obtain a better and more complete thermal contact between the extinguishing liquid and the compressed gas container than is accomplished in the extinguisher described in the above entitled application, and also to position and mount the gas contained in a manner which permits a simplification of the construction of the head portion of the extinguisher casing. 25

Referring to the drawings,—

Fig. 1 is a longitudinal central section of a fire extinguisher embodying the improvements of the present invention;

30 Figs. 2 and 3 are fragmentary cross sections on lines 2—2 and 3—3, respectively, of Fig. 1 and on a larger scale;

Fig. 4 is a fragmentary axial section illustrating the action of the punch in perforating the compressed gas container. 35

Like reference characters designate the same parts wherever they occur in all the figures.

The extinguisher shell comprises a head 40 portion 1 and a body portion 2, the former being conveniently made as a casting and the latter as a sheet metal tube, drawn or fabricated with a bottom head 3 and suitably secured to the head 1 by means well known in the art. Such head terminates in an open neck externally threaded, to which is applied a cap or cover 4 removable for charging the extinguisher. In the side of the head is formed a passage 5 to which is connected a 45 flexible discharge tube 6. The passage 5 opens into the interior of the casing and is controlled by a valve 7 of any suitable character, preferably spring closed and arranged to be opened by a sufficiently high internal 50 pressure.

The pressure for discharging the extinguisher is furnished by a highly compressed gas confined in a cartridge or container 8, preferably having continuous integral walls completely enveloping the compressed gas- 60 eous charge and made by welding together an initially separate body and cap, after filling with the gas, as explained in my prior applications for Letters Patent, Serial No. 692,468, filed February 13, 1924, and Serial 65 No. 64,047, filed October 21, 1925. The pressure charge is preferably carbon dioxide gas compressed to a pressure of 600 to 800 pounds per square inch. This container or cartridge is externally threaded adjacent to 70 one end and is screwed into the lower end of a tube 9 which is internally threaded at its opposite end and screwed to a boss 10 projecting from the inner side of the cover 4. The tube 9 is formed with an interior conical flange 11 which terminates at such a distance within the tube that its edge is adapted to bear on the end wall of the cartridge and make tight engagement therewith when the cartridge is screwed far enough into the tube 80 for secure attachment. The complementary threads of the cartridge and tube are suitably located and extended sufficiently to obtain this result. In the outer walls of the tube 9, surrounding the interior flange 11 85 are one or more openings 12 sufficiently large in area to permit entrance of the extinguishing liquid into contact with the end of the cartridge when the extinguisher is inverted for discharging. 90

The tube 9 is also provided at one side with a boss 13 in which is a passageway 14 opening into the interior space of the tube within the flange 11, but not communicating with the space outside of the flange. A pipe or 95 tube 15 is screwed or otherwise tightly fastened in the end of the passageway 14 and extends nearly to the bottom head 3 of the extinguisher in order to conduct the gas, when released, through the extinguishing 100 liquid without mixing therewith and to deliver the gas above the surface level of the liquid, the extinguisher being then inverted.

There is also arranged centrally within the tube 9 and connected with its walls by 105 arms 16, a plunger guide 17, the function of which is to guide the punch 18 by which the cartridge is punctured at the time of discharge.

The punch above mentioned is formed on 110

a plunger 19 which passes through a stuffing box 20 in the cover and carries a head 21 on its outer end. The punch proper is cylindrical, slightly tapered at its extremity 5 22 and having a cutting edge on its end, the area of which is nearly as large as the cylindrical part. It has a shallow recess 23 in one side adjacent to the tapered extremity to furnish a channel of restricted and predetermined area for escape of the gas.

In use the extinguisher, having previously been charged with a suitable non-inflammable liquid, which will not freeze at extremely low temperatures, such as carbon 15 tetrachloride, or an aqueous salt solution having a low freezing point, is inverted and the protruding end of the punch plunger is struck against some solid object. The punch is thereby thrust through the adjacent end 20 wall of the cartridge, which is preferably made of reduced thickness over an area somewhat larger than that of the punch and in line therewith. The cutting end of the punch then severs a disk from the cartridge 25 head and its tapered portion crowds the rim of the hole so formed into tight engagement with the sides of the cylindrical part of the punch, so that the punch is held by friction and will not be forced out of the cartridge by the fluid pressure therein. The groove 23, having been carried by the movement of the punch across the head of the cartridge, provides a restricted channel 30 through which the compressed gas may escape at a retarded rate approximately equal to the rate of discharge of the extinguishing liquid past the outlet valve 7.

After leaving the cartridge, the path of least resistance for the gas is through the 40 relatively wide passage 14 and bore of the tube 15, to the open space above the liquid level adjacent to the inverted bottom head 3; the rim of the flange 11 being so close against the cartridge head as to prevent, wholly or 45 substantially, escape of the gas between them. The extinguishing liquid is admitted through the openings 12 to the space around the flange 11 and contiguous to the cartridge head, when the extinguisher is charged, if 50 filled to a level above the cartridge, and in any case upon inversion of the extinguisher. Thus the cartridge is enveloped in the liquid during discharge, and particularly the major part of its head, from the circumference to 55 a point as near as possible to the outlet channel, and remains in contact with the liquid until the compressed gas has been practically all discharged. Hence the heat of the liquid is conducted through the walls 60 and head of the cartridge to the escaping gas, as the temperature of the latter becomes lowered by expansion, and the gas is thereby prevented from solidifying even though 65 reduced in temperature to a point at which it would freeze and block up the outlet

channel if the provisions herein described or equivalent provisions were not made for permitting access of the liquid to the head of the cartridge.

I have shown and described the interior 70 flange 11 as being conical. This is a simple and desirable form, but obviously it could be modified without departure from the spirit of the invention. Essentially the flange 11 provides an edge or lip which bears against 75 the cartridge head in a line closely surrounding the path of the punch, or at least, well within the circumference of the head, and excludes the liquid from the space into which the gas is discharged, leaving an annular 80 area of the cartridge head which comprises the major part of the entire area of the head, exposed to contact with the liquid. Provided this condition is preserved, the offset flange or wall 11 could be made of other 85 forms than the conical form shown.

It will be observed that the head 1 of the casing is of simple form, wholly open in its interior and without any internal structure for supporting the cartridge and gas conducting tube 15, these elements being supported entirely by the tube 9, which in turn is secured to and held by the cover. The tube 9, cover, cartridge and tube 15 may be assembled outside of the extinguisher casing and applied to the latter as a unit.

What I claim and desire to secure by Letters Patent is:

1. A fire extinguisher of the type employing an extinguishing liquid and compressed gas as the agent for expelling the liquid, said extinguisher having means in its normally upper part for supporting a compressed gas cartridge and being invertible for use, means for puncturing the head of the cartridge which is lowermost when inverted, partitioning means separating the space into which gas may flow from the punctured cartridge, from the space in which liquid is contained, the cartridge being in the latter space and surrounded by the liquid when the extinguisher is inverted, and the partitioning means being arranged to permit contact of the liquid with the cartridge head over the surface of the latter around the point of escape of the gas, and conducting means for leading gas from the former space into the inverted bottom part of the extinguisher above the level of the liquid.

2. A fire extinguisher of the class employing an extinguishing liquid and a charge of compressed gas for expelling the liquid, including means for holding a closed cartridge containing compressed gas, means for puncturing the cartridge to release the gas, and partitioning means for separating the space into which gas may flow from the punctured cartridge, from the space containing the extinguishing liquid, said partition-

ing means being disposed to permit access of the liquid to substantially the entire external surface of the cartridge except an area sufficiently large to be entered by the 5 puncturing means, when the extinguisher is inverted.

3. A fire extinguisher of the type including a cartridge containing compressed gas as the impelling agent for the extinguishing 10 liquid and adapted to be inverted for use, said extinguisher having internal means separating the space within which the extinguishing liquid is contained from the space into which gas is initially discharged from 15 the cartridge, and puncturing means adapted to penetrate a wall of such cartridge, the said internal separating means being disposed to permit access of the liquid, when the extinguisher is inverted, to the said wall 20 over an area well within the circumference thereof, while excluding the liquid from that part of the wall through which the puncturing means passes.

4. A fire extinguisher comprising a shell 25 adapted to contain extinguishing liquid and a cartridge holding a charge of compressed gas for expelling the liquid when released, a holder for the cartridge embracing one end thereof and including an interior flange 30 making a complete circuit about an interior space and arranged to bear on the head over an outline at the end of such space which encloses an area substantially less than the area of such head and to exclude the extinguishing liquid from such enclosed area 35 and from the adjacent space enclosed by the flange, said holder being of open construction adequate to permit access of the extinguishing liquid to the cartridge head outside 40 of said flange, and puncturing means arranged and operable to penetrate the cartridge head in the area surrounded by the flange.

5. A fire extinguisher comprising a shell 45 having an open end, a cap for said shell, a sleeve secured to the cap extending into the shell and having an open end adapted to receive and secure a compressed gas cartridge, said sleeve having also an interior

flange or partition arranged to make contact with the head of such cartridge on an outline surrounding an area substantially less than that of the cartridge head, and the sleeve between its cartridge receiving end and the zone from which said flange 55 springs being of open construction to admit the extinguishing liquid, the sleeve having also an outlet leading from the interior space of the sleeve within the flange.

6. An extinguisher comprising a shell 60 having an open end, a cap detachably mounted on said open end and having an interior threaded boss, a cartridge holding sleeve detachably screwed to said boss and extending into the shell, being open and internally threaded at its opposite end to receive and secure a cartridge containing compressed gas, the sleeve having an internal annular flange extending from its sides provided with a contracted rim adapted to make 70 contact with the head of the gas cartridge, and the sleeve having an opening in its side between the cartridge receiving end and the zone from which said flange 75 springs and also having a gas outlet from the interior space within the flange.

7. A fire extinguisher of the class employing an extinguishing liquid and a cartridge containing a charge of compressed gas for supplying pressure to expel the 80 liquid, said extinguisher comprising a cover for its charging opening and a puncturing tool for making an opening in the cartridge, a holder for the cartridge separate from the cover adapted to hold the cartridge enveloped 85 in the extinguishing liquid when the extinguisher is inverted and having means for permitting access of the liquid to the cartridge head around and near the area penetrated by said puncturing tool, while maintaining a separation between the liquid containing space of the extinguisher and the space into which the gas is discharged from the punctured cartridge.

In testimony whereof I have affixed my signature.

ARTHUR C. BADGER.
